Hardway, Cather
ATTORNEY.

UNITED STATES PATENT OFFICE.

OLIVER W. WILCOX, OF HOUSTON, TEXAS.

OPERATING TABLE.

Application filed June 30, 1922. Serial No. 571,929.

To all whom it may concern:

Be it known that I, OLIVER W. WILCOX, citizen of the United States, residing at Houston, in the county of Harris and State 5 of Texas, have invented certain new and useful Improvements in an Operating Table, of which the following is a specification.

This invention relates to new and useful 10 improvements in an operating table.

One object of the invention is to provide a table specially designed for use by chiropractors.

Another object of the invention is to provide 15 a table which may be folded up into compact space and which is therefore readily portable.

A further feature of the invention resides 20 in the provision of a table of the character described having a rigid framework, but provided with a yieldable or flexible body support, by means of which the entire body 25 of the patient and all of its members will be supported on flexible supporting members thus adding to the comfort of the patient while being operated upon.

A still further feature of the invention resides 30 in the provision of an adjustable flexible chest support which may be easily adjusted to accommodate any patient.

With the above and other objects in view the invention has particular relation to certain novel features of construction, arrangement of parts and use, an example of which 35 is given in this specification and illustrated in the accompanying drawings, wherein:—

Figure 1 shows a plan view of the table partially in section and with certain parts broken away.

Figure 2 shows a side view thereof partially in section.

Figure 3 shows an enlarged view of one of the leg joints.

Figure 4 shows a transverse sectional view 45 taken on the line 4—4 of Figure 1.

Figure 5 shows a transverse sectional view taken on the line 5—5 of Figure 1.

Figure 6 shows an enlarged fragmentary view of the table and,

Figure 7 shows a side view of the complete table in partially collapsed position.

In the drawings the numerals 1, 1 designate the side members of the foot portion of the table, and the numerals 2, 2 designate 55 the side members of the body portion of the table, said respective side members

being connected by the cross rods 3, 3 and 4, 4. The respective side members 1 and 2 are connected together by swiveling connections or joints as 5, 5. In construction the 60 foot portion of the framework is somewhat narrower than the body portion, as shown.

The side members 1, 1 are supported by two pairs of legs 6, 6 and the body portion of the framework is supported by the legs 65 7, 7. Each pair of legs 6 has a brace rod 8 connecting them, and the legs 7 are connected by a brace rod 9. The pairs of legs 6, 6 and 7, 7 are pivoted to the framework and swing as a unit when it is desired to 70 swing them into supporting or collapsed position. The upper end of each leg is bifurcated and depending from the framework are the flat downwardly flared hinge members 10, 10 and 11, 11 which fit into the 75 slots between the fingers of said bifurcated ends of the legs 6 and 7, and are pivoted thereto by means of the respective pins 12 and 13, and locking rings 14 and 15 are provided which are adapted to fit over the upper 80 ends of the legs and lock them in supporting position, the members 10 and 11 being flared sufficiently to hold said rings in locking position.

When it is desired to collapse the table the frame members 1 and 2 85 are folded together, operating on the swiveling connections 5 and the rings 14 and 15 are then released from locking position and the legs folded closely up against the folded frame, as indicated in Figure 7. A strong 90 pull spring 16 is provided which connects the rods 8 and which will automatically fold the legs 6 into collapsed position when the locking rings 14 are released from locking position. The framework 1 supports a 95 flexible covering 17 which is attached at its sides and ends to the corresponding side members 1 and cross bars 3. This is preferably formed of leather, fabric, or other flexible material and forms a comfortable support for the limbs of the patient. The numeral 18 designates the head rest for the patient which is attached to the cross rod 4 and to the side members 2, 2, as shown 100 in Figure 1. This head rest is narrowed and elongated forming the abdomen support 19 which extends underneath the limb support 17 and is connected to the cross rod 3 at the foot end of the table by the strong pull springs 20, 20. The head rest and 110 abdomen support are formed of leather, fabric, or other flexible material which is strong

enough to support the patient, but flexible enough to be comfortable. The patient usually lies face downwardly and an opening 21 is provided in the head rest for breathing purposes.

The legs 7 are adjustably connected to the side members 2, 2. In order to accomplish this slidable sleeves 22, 22 are mounted on said side members to which said legs 10 are pivoted, in the manner hereinbefore explained and a transverse breast support 23 is connected to said sleeves. This breast support consists of a comparatively wide belt formed of leather, fabric or other flexible material which is fitted around the sleeves 22 and its free ends laced together underneath, as shown. This breast support may be adjusted to the desired position by adjusting said sleeves on the side members 2 and the supporting legs 7 are made adjustable with it inasmuch as they will thereby at all times be directly underneath the main weight of the body.

What I claim is:—

1. An operating table including a framework, supporting legs depending from the framework at one end, a pair of supporting legs depending from the framework at its other end and being adjustable lengthwise thereon, a transverse breast support formed of flexible material and connected to, and adjustable with said last mentioned legs, a head support at one end of said framework, a leg support at the other end thereof, and an intermediate abdominal support, said supports being formed of flexible material.

2. An operating table including a frame-

work, supporting legs depending from the framework at one end, a pair of supporting legs depending from the framework at 40 its other end and being adjustable lengthwise thereon, a transverse breast support formed of flexible material and connected to, and adjustable with said last mentioned legs, a head support at one end of said 45 framework, a leg support at the other end thereof, and an intermediate abdominal support, said supports being formed of flexible material, said abdominal support being connected at one end to the head support, and 50 yieldable means connecting the other end of said abdominal support to the corresponding end of the framework.

3. An operating table including a framework whose side members have swiveling 55 joints in transverse alignment, supporting legs depending from the framework at one end, a pair of supporting legs depending from the framework at its other end and being adjustable lengthwise thereon, a transverse breast support formed of flexible material and connected to, and adjustable with 60 said last mentioned legs, a head support at one end of said framework, a leg support at the other end thereof, and an intermediate abdominal support, said supports being formed of flexible material.

In testimony whereof I have signed my name to this specification in the presence of two subscribing witnesses.

OLIVER W. WILCOX.
